CLAIM

The ornamental design for a handle face for combination utensil, as shown and described.

DESCRIPTION

FIG. 1 is a front perspective view of a handle face for a combination utensil in accordance with a first embodiment of the present design.

FIG. 2 is a rear perspective view thereof.

FIG. 3 is a top plan view thereof.

FIG. 4 is a bottom plan view thereof.

FIG. 5 is a right side elevational view thereof.

FIG. 6 is a front perspective view of a handle face for a combination utensil in accordance with a second embodiment of the present design.

FIG. 7 is a rear perspective view of the second embodiment.

FIG. 8 is a top plan view of the second embodiment;

FIG. 9 is a bottom plan view of the second embodiment; and, FIG. 10 is a right side elevational view of the second embodiment.

The broken lines are shown for illustrative purposes and form no part of the claimed design.
